UNITED STATES PATENT OFFICE.

WILLIAM BOEKEL AND JULIUS BOEKEL, OF PHILADELPHIA, PENNSYLVANIA.

DESIGN FOR A NEBULIZER-FRAME.

SPECIFICATION forming part of Design No. 33,349, dated October 9, 1900.

Application filed August 15, 1900. Serial No. 26,993. Term of patent 14 years.

To all whom it may concern:

Be it known that we, WILLIAM BOEKEL and JULIUS BOEKEL, citizens of the United States, residing at Philadelphia, in the county of Philadelphia and State of Pennsylvania, have invented and produced a certain new and useful Design for Nebulizer-Frames; and we do hereby declare the following to be a full, clear, and exact description of the invention, such as will enable others skilled in the art to which it appertains to make and use the same.

The accompanying drawing, forming part of this specification, illustrates a perspective view of a nebulizer-frame conforming to our design, the leading or material feature whereof consists in a frame composed of a series of arched tubes meeting at their upper ends in a common tubular center and connected below by straight horizontal radial tubes extending to a central vertical tube.

A designates the downwardly-arching tubes, B the tubular center in which they meet and which has a downward straight extension E, a curved short tubular branch F, and a straight short lateral branch G, the central vertical tube being designated D and the straight horizontal radial tubes C.

Having thus described our design, what we claim as new, and desire to secure by Letters Patent, is—

The design for a nebulizer-frame, as herein shown and described.

In testimony whereof we affix our signatures in presence of two witnesses.

WM. BOEKEL.
JULIUS BOEKEL.
